UNITED STATES PATENT OFFICE.

ROBERT CARL RAHM, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

BRAIDING-MACHINE.

933,341.

Specification of Letters Patent.

Patented Sept. 7, 1909.

Application filed April 6, 1908. Serial No. 425,329.

To all whom it may concern:

Be it known that I, ROBERT CARL RAHM, a citizen of the United States, and a resident of the borough of Wyomissing, in the county 5 of Berks and State of Pennsylvania, have invented certain new and useful Improvements in Braiding-Machines, of which the following is a specification.

My invention relates to braiding machines 10 and my main object is to provide an improved construction whereby two or more tubular braids may be formed simultaneously, either separately, or unitedly in whole or part as a compound braid; with capacity for changing at will from the separate 15 to the compound form for desired portions of the length produced; and with provision for introducing cores, as electric conductors, in the tubular parts, as required for telephone cords or similar purposes.

The invention is fully described in connection with the accompanying drawings, and the novel features are specifically pointed out in the claims.

Figure 1 is a plan view of a braiding machine embodying my invention. Figs. 2 and 3 are diagrammatic views indicating different braiding-carrier movements which are provided for by proper manipulation of the 25 switches indicated in Fig. 1; Fig. 2 being arranged for producing three separated tubular braids, and Fig. 3 for uniting these in a compound braid. Fig. 4 indicates the inner and outer braiding-carrier movements 30 provided for; whereby two separate concentric braids may be produced. Figs. 5 and 6, and Figs. 7 and 8, are similar views to Figs. 2 and 3, indicating modifications providing respectively for four tubular 35 courses and two tubular courses arranged in each case to be either operated as separate courses or run together for forming compound braids. Figs. 9 and 10 are separate views of parts of the novel switch 40 operating mechanism employed, the connections to which are indicated in Fig. 1.

Referring to Fig. 1, it will be understood that drive-gears for the bobbin-carriers are mounted as usual between the top-plate 1 50 of the machine and a bottom plate, not shown, and that the ordinary braiding mechanism involved is well known in its general features; so that only the special arrangement of the race-circle courses and of the 55 controlling switches and particular switch

operating mechanism shown, constituting the novel features of my invention, need be specifically described.

It will be seen that in Fig. 1 three separate tubular courses are provided, each comprising, as shown, eight connecting race-circles; the race-circles of one course being indicated by the reference character 2, of a second course by 3, and of the third course by 4. These separate courses are grouped together 60 so that two adjoining race-circles of each course (marked respectively 2^a, 3^a, and 4^a), are connected in a circular series around a common braiding center 6; these six connected race-circles, by proper setting of 65 the switches shown, being adapted to serve as a separate inner carrier-course as indicated in Fig. 4. The three series of race-circles 2, 3, and 4, are further connected by uniting race-circles 2^b, 2^b, of one course with 70 adjacent race-circles 3^b and 4^b of the other two courses, and also uniting race-circles 3^c and 4^c of the latter courses; thus enabling an outer carrier-course, as indicated in Fig. 75 4, to be formed by proper setting of the 80 switches. The switches marked 10, 11 and 12, are placed at the connecting points of the race-circles as indicated in Figs. 1 and 4, so as to enable each approaching carrier to be directed as desired, the movements of the 85 switches being preferably controlled by special operating mechanism as hereafter described. A core-guide 18 is provided at the center of each race-circle course 2 and 3, for the passage of a cord or of a conducting wire 90 around which the tubular braids are to be formed as is well known in connection with the manufacture of telephone cords.

The operation of the machine in manufacturing telephone cords will be readily 95 understood by reference to Figs. 2 and 3. Two uncovered wires being supplied through the core-guides 18 to the central braiding point (6) as usual, the carriers are operated, by proper setting of the switches, in the manner indicated in Fig. 3, to separately cover these wires and at the same time unite them in a compound braid; certain carriers being directed in the outer course as indicated by the dotted line; certain others on each separate course 2, 3, or 4, as indicated by the solid lines; and certain others upon the inner course as indicated by the dot-and-dash line; the result being the formation of three tubes, 105 two of which separately cover the core-wires, 110

and all of which are united in a compound braid. When a sufficient length of this form has been produced, the run of the carriers is changed to that indicated in Fig. 2, three 5 separate tubular braids being formed, two of which inclose the core-wires while the third one is empty and adapted to serve as a tie-cord as usual.

The three double-switches 10 (Fig. 1), on 10 switch-shafts 20, are connected by rods 21 so as to be simultaneously operated; and the six single switches 12 are similarly connected by rods 22. The switches 10 are moved by a main rod 23 attached to a cam-operated lever 15 24, and the switches 12 by a main rod 25 attached to a second cam-operated lever 26. The cam 27 (Figs. 1, 9 and 10) for operating both of these levers, is feathered upon a cam-shaft 28 upon which is fixed a gear wheel 29 20 arranged in mesh with the carrier drive-gears, and said cam is formed with an intermediate neutral portion 27^a upon which one or other of said levers rides idly while the other lever is being swung by the cam; the 25 latter being automatically adjustable longitudinally on its shaft 28 into proper position for operating one or other of the levers as desired. This adjustment of the cam is effected as indicated by a lever 29^a to which a 30 properly timed rocking movement is imparted as required through rods 30, 31 by any suitable mechanism, not shown, so that the respective switches will be positively and directly set. It will be understood that the 35 so-called "blind switches" 11 are merely pivoted parts swung by the carriers themselves to properly complete the race-way at the junctions.

It is obvious that my improved machine 40 may be employed for other uses than that particularly referred to above; and that it may be readily modified without departing from the invention. For instance in Figs. 5 and 6, the employment of four different 45 series of race-circles, 2, 3, 4 and 5 is indicated, instead of three as previously described; and in Figs. 7 and 8, two only are indicated as embodying the main feature of my invention. The special switch operating 50 mechanism shown is adapted to effect the particular switch movements required in the positive and simple manner practically essential to rapid and satisfactory braiding as described, but different mechanism, operated 55 for instance by the well-known jacquard apparatus might be substituted to effect these movements.

What I claim is:—

1. A braiding machine comprising two or

more independently-operative tubular carrier-courses, two race-circles from each of said courses being connected to form an endless inner series, and switches at the connecting points of said courses, substantially as set forth. 60

2. A braiding machine comprising a number of independently-operative tubular carrier-courses grouped around a common center, two race-circles from each of said courses being directly connected to form an endless inner series and the remaining race-circles being connected to form an endless outer series, and switches at the connecting points of said courses, substantially as set forth. 70

3. A braiding machine comprising a number of independently-operative tubular carrier-courses grouped around a common center, two race-circles from each of said courses being directly connected to form an endless inner series and the remaining race-circles 80 being connected to form an endless outer series, core-guides at the centers of said courses and switches at the connecting points of said courses, substantially as set forth. 75

4. A braiding machine comprising a number of tubular carrier-courses grouped around a common center, two race-circles from each of said courses being directly connected to form an endless inner series and the remaining race-circles being connected to form an endless outer series, separate series 90 of connected switches at the connecting points of said courses, a separate operating lever for each of said series of switches, and a continuously rotated and intermittently reciprocated cam engaging said levers to operate the same alternately substantially as set forth. 95

5. In a braiding machine comprising two series of connected switches, separate operating levers for the respective series and a continuously rotated and intermittently reciprocated cam engaging said levers to operate the same alternately substantially as set forth. 100

6. In a braiding machine comprising two 105 series of connected switches, separate operating levers for the respective series and a continuously rotated and intermittently reciprocated cam having a neutral intermediate portion whereby said levers are alternately operated or held in determined position substantially as set forth. 110

In testimony whereof, I affix my signature, in the presence of two witnesses.

ROBERT CARL RAIHM.
